(57) **CLAIM**

We claim the ornamental design for the baseball glove protector and pocket shaper apparatus, as shown and described.

DESCRIPTION

FIG. 1 is a front, right, and top perspective view of the baseball glove protector and pocket shaper apparatus in a first state;

FIG. 2 is a front elevational view of the baseball glove protector and pocket shaper apparatus in the first state; FIG. 3 is a rear elevational view of the baseball glove protector and pocket shaper apparatus in the first state; FIG. 4 is a left side elevational view of the baseball glove protector and pocket shaper apparatus in the first state; FIG. 5 is a right side elevational view of the baseball glove protector and pocket shaper apparatus in the first state; FIG. 6 is a top plan view of the baseball glove protector and pocket shaper apparatus in the first state; FIG. 7 is a bottom view of the baseball glove protector and pocket shaper apparatus in the first state; FIG. 8 is a perspective view of the baseball glove protector and pocket shaper apparatus in a second state where the baseball glove protector and pocket shaper apparatus is used to cover a baseball glove, with part of the baseball glove shown in broken lines;

FIG. 9 is the perspective view of the baseball glove protector and pocket shaper apparatus in the second state where the baseball glove protector and pocket shaper apparatus is used to cover a baseball glove, with part of the baseball glove shown in broken lines and with a section cut line 10-10 shown;

FIG. 10 is cross section of the view of FIG. 9, with the baseball glove shown in broken lines;

FIG. 11 is a perspective view of the baseball glove protector and pocket shaper apparatus in the first state where a ball of the baseball glove protector and pocket shaper apparatus is inserted into the baseball glove, with part of the baseball glove shown in broken lines; and,

FIG. 12 is a perspective view of the baseball glove protector and pocket shaper apparatus in a third state where a ball of the baseball glove protector and pocket shaper apparatus has been inserted into the baseball glove, with part of the baseball glove protector and pocket shaper apparatus wrapped around the baseball glove, and with part of the baseball glove shown in broken lines.

The dash-dot-dash broken lines showing of a baseball glove in FIGS. 8-12 illustrate environmental structure and form no part of the claimed design.

The dash-dash broken lines depict stitching and form part of the claimed design.

1 Claim, 11 Drawing Sheets
